ABSTRACT OF THE DISCLOSURE

An isostatic powder press for forming toilet tanks or other articles having holes formed therethrough. One of the die mechanisms in the press is provided with an annular sleeve which moves into the powder during the compaction stroke to entrap the powder and form a hole through the finished article. The hole is formed without stressing the compacted article, thus minimizing the tendency for cracks to occur adjacent the hole during the glazing and firing periods.

THE DRAWINGS

FIG. 1 is a sectional view taken through a press constructed according to the invention. FIGS. 2, 3, and 4 are fragmentary sectional views of other press constructions utilizing the invention.

FIG. 1 in greater detail

There is shown in FIG. 1 an isostatic powder press comprising first and second separable die mechanisms 10 and 12 advanceable together to define a ceramic powder powder cavity 14, and retractable from each other to expose the formed article; in this case the article is a toilet tank having a bottom wall 16 and a peripheral side wall 18. The tank article is shown being formed in an upside down position, although it could be formed right-side up if desired. The die mechanisms separate on a parting line 15.

Die mechanism 10 comprises a rigid plastic or metallic core section 20 having a peripheral flange 22 which mates with an annular clamping plate 24, said plate 24 serving to anchor the peripheral flange 26 of a resilient deformable rubber membrane 28. The outer or upper surface 30 of the membrane forms a movable die surface for compressing powder with cavity 14. To effect outward and upward movement of membrane 30 there is provided in core 20 a fluid passage 32 leading to one or more fluid channels 34 in the core surface. Admission of pressure fluid into fluid passage 32 causes the membrane 30 to deform upwardly and outwardly, to thus compact the powder from the illustrated thickness to the thickness generally denoted by arrows 36. Line 38 denotes the interior surface of the final article after the compaction stroke.

Die mechanism 12 comprises a rigid mold member 40 having a female mold cavity surface 42 and an opening 44 which is normally closed by a cover member 46; member 46 forms part of the die mechanism during the compaction process. When cover member 46 is removed from member 40 powder can be introduced through opening 44, as by blowing or pouring procedures. Thereafter the die mechanisms 10 and 12 may be held together by force means 48 (clamps, vises, presses, etc.) and pressure fluid applied through passage 32 to deform the membrane 28 upward and outward, thus compacting the powder to the final thickness denoted by numeral 36.

Cover 46 carries one or more sleeves 50 thereon. During the compaction stroke of the membrane the lower peripheral end edge 52 of the sleeve causes powder to be

2

entrapped within the sleeve. At the end of the compaction stroke the membrane substantially engages the peripheral edge 52 of the sleeve, and the entrapped powder is substantially disconnected from the compacted article. Upon reverse movement of the membrane and removal of cover 46 from mold member 40, the entrapped powder is removed with sleeve 50, leaving a hole through the article. The shape of the hole (round, square, slot-like, etc.) will be determined by the shape of sleeve 50. The compacted article is dried, glazed and fired, as under conventional practice, to form a rigid useful ceramic article.

Prior to this invention holes were formed by means of cookie cutter implements pressed into the green uncured article. After glazing and firing, cracks sometimes developed because the hole-forming operation was performed after the article had been compacted. It is believed that during the hole-punching operation the material adjacent the hole was deformed or stressed to a greater extent than other portions of the article so that the higher stressed areas tended to expand or relieve themselves during the firing period, resulting in stress riser cracks.

By forming the holes during the compaction process 25 the stress riser cracks are eliminated. It is believed that this is because the sleeve 50 slices into the powder material as it is being compacted so that the powders can shift before they have become substantially welded together. Thus, the shifting of the powders occurs while 30 there is still room or space for the powders to avoid one another; at firing there are fewer stresses which have to be relieved.

FIG. 1 illustrates one form which the sleeve 50 can take in the practice of the invention. Another form is 35 shown in FIG. 2. As there shown, the sleeve is formed with an upper end wall 54 having airjet openings 56 therethrough. The purpose in these jet openings is to permit ejection of the entrapped powder after completion of the compaction operation. Thus, after cover 46 40 has been removed from opening 44 compressed air can be introduced through the opening 58 to produce jets of air against the interior back face of the powder disk. The airjets effectively discharge the powder disk and clean the sleeve 50 for the next cycle.

FIG. 3 illustrates another form which the sleeve can take. As shown in FIG. 3, the sleeve 50 is slidably retained within an opening in cover member 46 and is biased toward the membrane 28 by means of a compression spring 60. A plate 62 is suitably affixed to the cover 50 to retain the spring 60 in place.

The FIG. 3 sleeve 50 protrudes from the surface of die mechanism 12 the full initial thickness of the powder space. Thus member 28 engages the sleeve from the beginning of the compaction stroke until the end of the stroke. As the compaction movement takes place the sleeve 50 moves upwardly, and the spring 60 collapses accordingly. Spring 60 is of course a comparatively light spring, sufficient only to keep the sleeve 50 engaged with member 28 but ineffective to deter the membrane from its designated movement. At conclusion of the compaction operation a jet of air can be introduced through opening 64 to aid in removal of the powder entrapped within sleeve 50.

FIG. 4 illustrates an arrangement wherein sleeve 50 is carried by the membrane 28 rather than cover 46. During the compaction stroke the sleeve slices through the powder and entraps some of the powder to thus form the hole in the finished article. A depression 66 may be performed in cover 46 to accept some of the entrapped powder.

We claim:

1. In an isostatic powder press comprising first and second separable die mechanism advanceable together to define a ceramic cavity for unfired ceramic powder, and retractable from each other to expose the formed uncured article; said first die mechanism including a core, a deformable membrane carried by and lying against said core, and means for applying fluid pressure to the interior space between the core and membrane, whereby to cause said membrane to transmit a compacting force onto the powder in the cavity: the improvement comprising a sleeve having a lower peripheral end edge, said sleeve being carried by either the membrane or the second die mechanism, whereby said peripheral end edge of said sleeve directs powder into and entraps powder within the sleeve as the membrane undergoes its powder-compacting movement; said sleeve being of sufficient length as to be engaged with the membrane and the second die mechanism at the end of the compaction stroke, whereby said entrapped powder is non-compacted and is substantially disconnected from the compacted article to define a hole through the wall of the uncured article.

2. The press of claim 1 wherein the sleeve is carried on the second die mechanism.

3. The press of claim 1 wherein the second die mechanism is provided with airjet openings within the space circumscribed by the sleeve, whereby jets of air can act to dislodge compacted powder from within the sleeve.

4. The press of claim 2 wherein the sleeve is slidably

mounted within the second die mechanism for movement in the direction of its axis; the combination further comprising spring means biasing the sleeve toward the membrane, whereby compacting movement of the membrane causes said membrane to contact the sleeve before completion of the compacting stroke, and final movement of the membrane causes the sleeve to slide into the second die mechanism.

5. The press of claim 1 wherein the sleeve is carried by the second die mechanism, said sleeve having an axial protrusion from the second die mechanism equal to the final thickness of the compacted article, whereby the membrane substantially meets the sleeve as it finishes its compaction stroke.
